FILLING-FEELER MECHANISM.

1,249,277.

Specification of Letters Patent. Patented Dec. 4, 1917.

Application filed November 29, 1915. Serial No. 64,010.

To all whom it may concern:

Be it known that we, CLARE H. DRAPER and JONAS NORTHCROFT, citizens of the United States, residing at Hopedale, in the county 5 of Worcester and Commonwealth of Massachusetts, have invented certain new and useful Improvements in Filling-Feeler Mechanisms; and we do hereby declare the following to be a full, clear, and exact description 10 of the invention, such as will enable others skilled in the art to which it appertains to make and use the same.

The present invention relates to an improvement in filling feeler mechanisms for 15 looms.

One object of the present invention is to produce a filling feeler mechanism of such construction that the filling feeling operation may be performed with delicacy and 20 precision, to the end that all the filling carriers will be exhausted to a predetermined extent, irrespective of their sizes and positions in the shuttle. A further object of the invention is to produce a filling feeler 25 mechanism of such construction that it will not operate prematurely to effect a change in the operation of the loom. To the accomplishment of these objects and such others as shall hereinafter appear, the present 30 invention consists of the filling feeler mechanism hereinafter described and particularly pointed out in the appended claims.

In the accompanying drawings illustrating the preferred form of the invention, 35 Figure 1 is a plan of a portion of the left-hand end of a loom showing the application of the improved filling feeler mechanism thereto; Fig. 2 is a view in side elevation, partly in section, of the parts shown in Fig. 40 1; Fig. 3 is a plan of the parts illustrated in Fig. 1 showing the positions of the parts of the filling feeler mechanism upon predetermined exhaustion of filling; and Fig. 4 is a section taken on the line 4-4 of Fig. 1.

The loom to which the improved filling 45 feeler mechanism is applied may be of any usual or preferred construction and may be either a plain loom or an automatic loom. The loom illustrated in the drawings is of 50 the automatic weft replenishing type and comprises a lay 9 supported on a lay sword 10 for oscillation toward and from the breast beam 11. The lay 9 is provided in the usual manner with a shuttle box 12 in

which the shuttle 13 comes to rest, when 55 properly boxed, in position to permit the filling feeler mechanism to determine the extent to which the filling on the bobbin has been exhausted. A longitudinal slot 14 is cut in the front wall of the shuttle to permit the filling feeling operation. A rock 60 shaft 15, which is journaled in suitable bearings at the front side of the breast beam, extends across the front of the breast beam and is operatively connected at the other 65 end of the loom with the weft replenishing mechanism. Secured to the rock shaft 15 and projecting upwardly therefrom is an arm 16 to the upper end of which is pivoted a rock shaft actuator 18. The rock 70 shaft actuator 18, the arm 16 and the rock shaft 15 constitute what is hereinafter called the filling supply controlling means and their function is, when the filling in the active shuttle has been exhausted to a pre- 75 determined extent,—that is to say, when there is critical exhaustion of filling,—to initiate the operation of the weft replenishing mechanism and thereby cause the insertion of a fresh supply of filling in the shuttle. The parts above enumerated, their actuating mechanism and their mode of operation together with other loom parts shown 80 and necessary to a disclosure of the present invention, are of usual construction and well 85 known to those skilled in the art.

The improved filling feeler mechanism operates to determine the amount of filling in the active shuttle and, upon critical exhaustion of filling, to set in operation either 90 the filling supply controlling means, or means for stopping the loom. The filling feeler mechanism comprises a filling feeler generally indicated by the reference character 19, a controller 20, and a latch lever 21. 95 The filling feeler consists of a feeler lever 22 and a filling engaging member 23 having upon its rearmost extremity filling engaging teeth 24. The filling engaging member 23 is slidably mounted in two ears 26-27 projecting upwardly from the rearward part of the feeler lever. The filling engaging member 23 is yieldingly pressed toward the bobbin 28 by a light tension spring 29 encircling a shank 30 formed on the forward end of 100 the member. One end of the spring engages a shoulder formed between the member and the shank, and the other end of 105

the spring engages the ear 27. The rearward movement of the filling engaging member is limited by a stop pin 31. The feeler lever 22 is mounted upon a stationary vertical pivot pin 32 rising from a feeler lever plate 33 secured to a support 34. The support 34 is in the form of an angle iron and its depending web 35 is bolted to a bracket 36 fastened to the breast beam. A slot 37 cut in the forward end of the feeler plate 33 affords provision for adjusting the feeler lever forward and backward relatively to the controller 20 and the bobbin or filling carrier 28. The slot 37 also permits the feeler lever to be positioned in angular relation with the bobbin 28. A screw 38 passing through the slot 37 secures the feeler lever plate 33 in adjusted position on the support 34. A lug 39 on the under rear end of the plate 33 is received in a slot 41 formed in the support 34 and permits the forward and rearward adjustment of the plate 33 and also prevents the rear end of the plate from moving laterally. The above described construction is such that, when the filling engaging member receives the impact of the forwardly moving bobbin, the force of the impact is communicated to the feeler lever pivot substantially on a line connecting the pivot and the filling engaging end of the filling engaging member.

The latch lever 21 is mounted for movement on a vertical pivot pin 42 carried by the rear end of the rock shaft actuator 18. A compression spring 43 interposed between the latch lever and the rock shaft actuator tends to force the rear end of the latch lever into the path of movement of the weft hammer 25. The rear end of the latch lever is notched at 44 in order that it may be suitably engaged by the weft hammer at the proper time. A lug 45 projecting laterally from the forward end of the latch lever determines the operative position of the latch lever. The rear end of the latch lever is provided with a cam surface 46, whose function will be hereinafter described. The latch lever is articulated with the feeler lever by means of a connecting link 47. The right-hand end of the connecting link 47 passes through a hole in the head of a bolt 48 received in a threaded hole in the forward end of the latch lever. The left-hand end of the connecting link 47 engages a slot 49 formed in the forward end of the feeler lever. The pressure of the spring 43 is communicated to the feeler lever 22 by the link 47, the rear ends of the feeler lever and the latch lever moving to the left simultaneously. The pressure of the spring 43 is just sufficient to overcome the inertia of the two levers when the filling engaging member presses against the bare surface of the bobbin. When it is desired to adjust the feeler

lever and latch lever relatively to each other, the link 47 is disconnected from the feeler lever and the bolt 48 is turned in the threaded hole in the forward end of the latch lever.

The controller 20 is journaled in ears 50-51 for sliding movements toward and from the shuttle. The controller is yieldingly pressed toward the shuttle by a compression spring 52 of heavy tension relatively to the spring 43 and to the spring 29. The controller is received in a threaded hole in a hub 53 so that it may be adjusted relatively to the shuttle and feeler lever. A checknut 54 secures the controller in adjusted position. To facilitate its adjustment, the forward end 55 of the controller is slotted to receive a wrench. The rear end of the controller is struck by the shuttle springs 57 on each forward beat of the lay 85 when the shuttle is in the shuttle box opposite the filling feeler mechanism. The hub 53 carries a stop lug 58 which engages a shoulder 59 projecting laterally from the feeler lever 22. To prevent rotation of the controller 20 and therefore of the stop lug 58, a finger 60 projecting from the hub 53 loosely engages the under side of the support 34. The above described construction is such that at all times, except when the rear end of the controller is struck by the shuttle springs, the spring 52 forces the hub 53 against the rear end of the ear 50, thereby forcing the stop lug 58 against the shoulder 59 of the feeler lever and causing the feeler lever and the latch lever to remain in normal or inoperative position.

The filling feeler mechanism comes into operation on the forward beat of the lay 105 when the shuttle is boxed at the end of the lay opposite the filling feeler mechanism, to determine the amount of filling on the bobbin. The filling feeling operation takes place on what is known as the filling feeling beat of the lay. The filling strikes the filling engaging member immediately before the shuttle springs 57 strike the controller 20 and until the controller is struck by the shuttle springs, the filling feeler and the latch lever are kept in inoperative position. While any filling remains on the bobbin opposite the filling engaging end of the filling engaging member, the engagement of the teeth 24 of the filling engaging member with this filling prevents the spring 120 43 from turning the feeler lever 22 on its pivot. The filling engaging member is moved forward on each filling feeling beat of the lay a distance at least equal to the depth of the filling on the bobbin, and this forward movement of the filling engaging member diminishes proportionately as the filling is unwound. The controller is moved forward a constant distance at each filling feeling beat of the lay, and this distance is 130

just sufficient to permit the feeler lever to turn on its pivot to bring about the operation of the devices controlled by the filling feeler mechanism when the filling has been exhausted to a predetermined extent.

When the controller is forced forward by the shuttle springs, and the stop lug 58 is moved out of contact with the shoulder 59, the spring 43 tends to cause the filling engaging member to swing to the left. This tendency of the filling engaging member to swing to the left after it has been engaged by the filling and after the spring 43 has been relieved of the overpowering tension of the spring 53, would cause a chafing of the filling if it were permitted to continue during the whole engagement of the filling with the filling engaging member. To obviate this chafing of the filling by the filling engaging member, the weft hammer 25 engages the cam surface 46 and forces the rear end of the latch lever to the right and its forward end to the left, thereby relieving the feeler lever from the stress of the spring 43.

So long as a single winding of filling remains on the bobbin opposite the filling engaging member, the feeler lever is prevented from turning. Consequently, under propulsion of the spring 43, the filling engaging member follows along and in engagement with the unwound surface of the bobbin and is kept constantly in engagement with the end strand of the unwinding filling until the filling has been unwound to a predetermined point from the butt end of the bobbin, by which time the spring 43 has forced the notched end of the latch lever into the path of motion of the weft hammer 25; and on the next forward beat of the weft hammer, the filling supply controlling means is set in operation. This unwinding of the filling to a predetermined extent from the butt end of the bobbin results in all bobbins being unwound to a uniform, predetermined extent. Should there be any variation in the sizes of the bobbins, or should a bobbin be obliquely positioned in the shuttle, the yielding mounting of the feeler tip will prevent impairment of the accuracy of the filling feeling operation.

The present invention contemplates a filling feeler mechanism having a filling feeler mounted on a fixed vertical pivot, the filling engaging end of the feeler communicating the force of the impact it receives from its engagement by the filling to the pivot on which the feeler is mounted, in a line substantially parallel with the motion of the lay. As the filling approaches predetermined exhaustion, the filling engaging end of the feeler is caused to travel along and in engagement with the unwound surface of the bobbin by means acting to position a latch lever in the path of motion of the

weft hammer when the filling has been exhausted to a predetermined extent, so as thereby to set in operation the filling supply controlling means. A controller keeps the feeler and the latch lever in inoperative position until the feeler has been engaged by the filling, at which time the controller is disengaged from the feeler and the latch lever to permit them to attempt to set the filling supply controlling means in operation.

It is apparent, therefore, that the present invention may be embodied in other constructions than that shown in the drawings and described in the foregoing specification and yet be within the scope of the following claims.

What we claim is:

1. A loom having, in combination, a lay, a shuttle, a filling carrier, and a filling feeler mechanism comprising a fixed support, a filling feeler pivotally mounted on the support, a feeler controller slidably mounted on the support, and means for normally holding the controller in position to be struck by the shuttle and the feeler in the path of motion of the filling carrier.

2. A loom having, in combination, a lay, a shuttle, a filling carrier, and a filling feeler mechanism comprising a support, a filling feeler consisting of a feeler lever and a filling engaging member, and a feeler controller slidably mounted on the support and having provision for engagement with the feeler lever to hold it from turning until the filling engaging member has been engaged by the filling, the line joining the filling engaging end of the filling engaging member and the pivot of the feeler lever being in line with the pressure exerted by the filling on the filling engaging member.

3. A loom having, in combination, a lay, a shuttle, a filling carrier, and a filling feeler mechanism comprising a filling feeler consisting of a feeler lever pivoted on a fixed support and a filling engaging member yieldingly pressed toward the filling carrier, and a feeler controller arranged to be struck by the shuttle and having provision for holding the feeler lever from turning until the filling engaging member has been engaged by the filling.

4. A loom having, in combination, a lay, a shuttle, a filling carrier, and a filling feeler mechanism comprising a feeler lever and a filling engaging member, means tending to swing the lever longitudinally of the filling carrier, and a controller having provision for engagement with the feeler lever to prevent it from turning until the filling engaging member is engaged by the filling and being arranged to be struck by the shuttle to release the feeler lever to permit pivotal movement thereof.

5. A loom having, in combination, a lay, a shuttle, a filling carrier, and a filling feeler

- mechanism comprising a filling feeler consisting of a feeler lever and a filling engaging member slidably mounted on the feeler lever, and a feeler controller arranged to be struck by the shuttle for normally holding the feeler lever in position so that the filling engaging member may be struck by the filling carrier, and having provision for disengagement from the feeler lever when the controller is struck by the shuttle.
6. A loom having, in combination, a lay, a shuttle, a filling feeler mechanism comprising a sliding controller arranged to be engaged by the shuttle on each filling feeling beat of the lay, and a filling feeler, the controller and the filling feeler being constructed and arranged so that motion is imparted to the filling feeler by the controller, when the latter moves in one direction, but no motion is imparted to the filling feeler by the controller when the latter moves in the opposite direction.
7. A loom having, in combination, a lay, a shuttle, a filling carrier, and a filling feeler mechanism comprising a fixed support, a filling feeler consisting of a feeler lever pivoted on the support, and a filling engaging member yieldingly mounted on the lever for sliding movements toward and from the lay, and means for holding the feeler lever from turning until the filling has engaged the filling engaging member, the feeler lever being then prevented from turning by the coöperation between the filling and filling engaging member until the former has been exhausted a predetermined extent.
8. A loom having, in combination, a lay, a shuttle, a filling carrier, and a filling feeler mechanism comprising a filling feeler consisting of a feeler lever and a filling engaging member yieldingly pressed toward the filling carrier, and a feeler controller for normally holding the feeler lever in position so that the filling engaging member may be engaged by the filling carrier and arranged to be struck by the shuttle to release the feeler lever, said filling engaging member being adapted to be engaged by the filling and to be moved thereby relatively to the feeler lever at least a distance equal to the depth of the filling on the filling carrier at each filling feeling beat of the lay.
9. A loom having, in combination, a lay, a shuttle, a filling carrier, and a filling feeler mechanism comprising a filling feeler consisting of a feeler lever pivoted on a fixed pivot and a filling engaging member slidably mounted on the feeler lever, and a controller having provision for normally holding the feeler lever from turning, said controller being arranged to be struck by the shuttle and to be moved forward thereby a constant distance on each filling feeling beat, and said filling engaging member being arranged to move forward, on each filling

feeling beat, a distance diminishing proportionately to the unwinding of the filling.

10. A loom having, in combination, a lay, a shuttle, a filling feeler mechanism comprising a support, a filling feeler mounted on the support consisting of a feeler lever and a yieldingly mounted filling engaging member and a feeler controller slidably mounted on the support for normally holding the feeler lever in position so that the filling engaging member may be engaged by the filling carrier, the controller being constructed and arranged to be moved forward a constant distance on each filling feeling beat of the lay and the filling engaging member being constructed and arranged to move forward on each filling feeling beat of the lay a distance diminishing proportionately to the unwinding of the filling.

11. A loom having, in combination, a lay, a shuttle, a filling carrier, and a filling feeler mechanism comprising a filling feeler consisting of a feeler lever mounted on a stationary pivot and arranged in substantial parallelism with the path of motion of the lay, a filling engaging member slidably and yieldingly mounted on the feeler lever and arranged to be engaged by the filling carrier, and means for turning the lever when the filling approaches critical exhaustion.

12. A loom having, in combination, a lay, a shuttle, a filling carrier, and a filling feeler mechanism comprising a fixed support, a filling feeler consisting of a feeler lever pivoted on the support and a filling engaging member slidably and yieldingly mounted on the feeler lever, and a feeler controller slidably mounted on the support and arranged to be engaged by the shuttle and be moved forward a constant distance on each filling feeling beat of the lay.

13. A loom having, in combination, a lay, a shuttle, a filling carrier, and a filling feeler mechanism comprising a fixed support, a filling feeler consisting of a feeler lever pivoted on the support and arranged in substantial parallelism with the path of motion of the lay, and a filling engaging member yieldingly mounted on the feeler lever and arranged to be moved relatively thereto a distance at least equal to the depth of the filling on the filling carrier on each filling feeling beat of the lay.

14. A loom having, in combination, a lay, a shuttle, a filling carrier, and a filling feeler mechanism comprising a support, a plate adjustably secured to the support, a feeler lever pivoted on the plate, and a spring-pressed controller mounted on the support, the feeler lever and the controller having parts normally in separable engagement with each other, the whole being constructed and arranged so that when the plate is adjusted on a straight line toward or from

the lay, the feeler lever is adjusted angularly.

15. A loom having, in combination, a lay, a shuttle, filling supply controlling means, 5 a weft hammer and a filling feeler mechanism comprising a support, a controller, a pivoted filling feeler, a latch lever connected with the filling feeler to move laterally conjointly therewith and adapted to be engaged 10 by the weft hammer to actuate the filling supply controlling means, said latch lever being maintained in inoperative position until the filling has been exhausted to a predetermined extent.

15. 16. A loom having, in combination, a lay, a shuttle, weft supply controlling means, and a filling feeler mechanism comprising a filling feeler, consisting of a feeler lever and a filling engaging member slidably mounted on the feeler lever, a pivoted latch and a link connecting the feeler lever and the latch, said feeler lever and latch having provision whereby they are turned on their pivots parallelly.

25. 17. A loom having, in combination, a lay, a shuttle, filling supply controlling means, a weft hammer, and a filling feeler mechanism comprising a support, a filling feeler pivoted thereon, a controller mounted on 30 the support for normally holding the feeler from turning, a latch lever connected with the feeler and adapted to be engaged by the weft hammer to actuate the filling supply controlling means when the filling has 35 been exhausted to a predetermined extent, means connected with the controller for normally holding the latch lever in inoperative position, and means connected with the latch lever for imparting a pivotal movement to the filling feeler when the filling has 40 been exhausted to a predetermined extent.

18. A loom having, in combination, a lay, a shuttle, a filling feeler mechanism comprising a controller, a filling feeler, a latch, 45 means connected with said controller adapted to maintain the feeler and the latch in inoperative position until the feeler has been engaged by the filling, and means connected with said latch adapted to impart a pivotal movement to the feeler when the filling has 50 been exhausted to a predetermined extent.

19. A loom having, in combination, a lay, a shuttle and a filling feeler mechanism comprising a controller, a filling feeler, a latch, 55 and means connected with the feeler and the latch for moving them laterally in the same direction when the filling has been exhausted to a predetermined extent.

20. A loom having, in combination, a lay, 60 a shuttle, filling supply controlling means, a weft hammer, and a filling feeler mechanism comprising a support, a controller mounted for movement thereon, a filling feeler pivotally mounted thereon, a latch 65 lever adapted to be engaged by the weft

hammer to actuate the filling supply controlling means, means tending to turn the latch lever, said latch lever being maintained in inoperative position by the controller, and a connecting link through which the latch 70 lever moves the filling feeler on its pivot when the latch lever has been permitted to be moved into operative position in front of the weft hammer by the forward movement of the controller, upon predetermined 75 exhaustion of filling.

21. A loom having, in combination, a lay, a filling carrier, loom controlling means, a weft hammer, a latch lever operatively connected with the loom controlling means normally out of the path of motion of the weft hammer, a filling feeler, a link connecting the filling feeler and the latch lever, means for holding the filling feeler and the latch 80 lever in normal position until the filling 85 feeler has been engaged by the filling carrier, and means operative upon predetermined exhaustion of filling to turn the latch lever to position it in the path of the weft hammer.

22. A loom having, in combination, a lay, a shuttle, a weft hammer, a filling feeler mechanism comprising a controller, a filling feeler, and a latch, said latch having provision tending to impart a pivotal movement 95 to the feeler during the first part of the filling feeling operation and having provision for co-operation with the weft hammer whereby the latch is prevented from imparting a pivotal movement to the feeler during 100 the latter part of the filling feeling operation, so long as the filling feeler is engaged by filling.

23. A loom having, in combination, a lay, a shuttle, and a filling feeler mechanism 105 comprising a support, a feeler consisting of a feeler lever, and a filling engaging member slidably mounted on the lever, means tending constantly to turn the feeler lever on its pivot, and a controller mounted on 110 the support and arranged for engagement by the shuttle for holding the feeler lever against turning until the controller has been struck by the shuttle.

24. A loom having, in combination, a lay, 115 a shuttle, a filling carrier, filling supply controlling means, and a filling feeler mechanism comprising a filling feeler constructed and arranged to have a filling feeling movement longitudinally of the filling carrier, 120 means adapted to be actuated by a moving part of the loom to set in operation the filling supply controlling means, and a link connecting the filling feeler and the means for operating the filling supply controlling 125 means.

25. A loom having, in combination, a lay, a shuttle, and a filling feeler mechanism comprising a fixed support, a filling feeler consisting of a feeler lever pivoted on the 130

support, and a filling engaging member yieldingly mounted for sliding movements on the feeler lever, the line joining the filling engaging end of the filling engaging member and the feeler lever pivot being substantially parallel with the path of movement of the lay, and a controller for controlling the operation of the feeler.

26. A loom having, in combination, a lay, a shuttle, filling supply controlling means, and a filling feeler mechanism comprising a controller, a filling feeler, and a latch, the controller being adapted to maintain the feeler and latch in inoperative position until the feeler has been engaged by the filling, and the latch being adapted to set in operation the filling supply controlling means when predetermined exhaustion of filling has been indicated by the filling feeler.

27. A loom having, in combination, a lay, a shuttle, a filling carrier, and a filling feeler mechanism comprising a controller, a filling feeler including a filling engaging member, having provision whereby its filling engaging end may move longitudinally of the filling carrier, a latch, the controller being arranged to hold the filling feeler and the latch in inoperative position until the feeler has been engaged by the filling, and means acting on the latch and the filling feeler for causing the feeler to move so that its filling engaging member may move longitudinally of the filling carrier after the filling feeler and the latch have been released by the controller and the filling has been exhausted to a predetermined extent.

28. A loom having, in combination, a lay, a shuttle, and a filling feeler mechanism comprising a fixed support, a filling feeler consisting of a feeler lever pivoted on the support, and a feeler tip slidably mounted on the lever and yieldingly pressed toward the lay, a controller for normally holding the feeler in inoperative position, and means normally held in inoperative position by the controller for turning the feeler lever on its pivot to permit the filling engaging member to travel along the unwound surface of the filling carrier when the filling thereon has been exhausted to a predetermined extent.

29. A loom having, in combination, a lay, a shuttle, a filling carrier, and a filling feeler mechanism comprising a fixed support, a filling feeler pivotally mounted on the support, a feeler controller slidably mounted on the support and arranged to be struck by the shuttle, said feeler controller having provision for engaging the filling feeler, and means for yieldingly pressing the feeler controller toward the lay to hold the filling feeler in position to be engaged by the filling carrier.

30. A loom having, in combination, a lay, a shuttle, a filling carrier, and a filling

feeler mechanism comprising a fixed support, a filling feeler pivotally mounted on the support, a feeler controller slidably mounted on the support having provision for engagement with the filling feeler, and means for yieldingly pressing the controller toward the lay to move it into engagement with the feeler, said controller being arranged to be struck by the shuttle and moved out of engagement with the feeler.

31. A loom having, in combination, a lay, a shuttle, a filling carrier, and a filling feeler mechanism comprising a fixed support, a filling feeler pivotally mounted on the support, means operative to turn the feeler when the filling has been exhausted to a predetermined extent, means for normally holding the feeler in position to be struck by the filling carrier, and a feeler controller slidably mounted on the support and arranged to be struck by the shuttle to permit the feeler turning means to attempt to turn the feeler.

32. A loom having, in combination, a lay, a shuttle, a filling carrier, and a filling feeler mechanism comprising a fixed support, a filling feeler pivotally mounted on the support, and a feeler controller slidably mounted on the support normally in engagement with the filling feeler for holding the feeler in normal position, said controller being arranged to be struck by the shuttle to be disengaged from the filling feeler after the feeler has been struck by the filling carrier.

33. A loom having, in combination, a lay, a shuttle, and a filling feeler mechanism comprising a fixed support, a filling feeler consisting of a feeler lever pivoted on the support, and a filling engaging member yieldingly mounted for sliding movements on the feeler lever, the line joining the filling engaging end of the filling engaging member and the feeler lever pivot being substantially parallel with the path of movement of the lay.

34. A loom having, in combination, a lay, a shuttle, a weft hammer, filling supply controlling means, and a filling feeler mechanism comprising a pivoted filling feeler, a feeler controller, a latch connected with the filling supply controlling means, a link connecting the filling feeler and the latch, said controller having provision for holding the filling feeler and the latch in normal position until the filling feeler has been engaged by the filling carrier, and means operative upon predetermined exhaustion of filling to turn the latch and the filling feeler to move the latch into the path of the weft hammer to actuate the loom controlling means.

35. A loom having, in combination, a lay, a shuttle, and a filling feeler mechanism comprising a filling feeler consisting of a

feeler lever and a filling engaging member yieldingly mounted on the feeler lever and pressed toward the shuttle, means for preventing the feeler lever from turning until 5 predetermined exhaustion of filling, and a controller arranged to be engaged by the shuttle to permit the feeler lever to turn when the filling has approached critical exhaustion.

10 36. A loom having, in combination, a lay, a shuttle, a filling carrier, and a filling feeler mechanism comprising a filling feeler consisting of a feeler lever pivoted on a fixed

support, a filling engaging member slid- 15
ingly mounted on the feeler lever and yield-
ingly pressed toward the lay, means opera-
tive on predetermined exhaustion of filling
to turn the feeler lever so that the filling
engaging member may move longitudinally
along the denuded surface of the filling car- 20
rier in engagement therewith and with the
exhausting filling, and means for holding
the filling feeler in normal position until
it has been engaged by the filling carrier.
